Edward Rutt
INVENTOR
BY *Victor J. Evans*

ATTORNEY

UNITED STATES PATENT OFFICE.

EDWARD RUTT, OF SONOMA, CALIFORNIA.

RADIATOR CAP.

Original application filed April 3, 1922, Serial No. 549,131. Divided and this application filed April 9, 1923. Serial No. 630,898.

To all whom it may concern:

Be it known that I, EDWARD RUTT, a citizen of the United States, residing at Sonoma, in the county of Sonoma and State 5 of California, have invented new and useful Improvements in Radiator Caps, of which the following is a specification.

This invention relates to radiators for motor vehicles and is a division of my prior 10 application for patent on radiators filed April 3rd, 1922, Serial #549,131.

The present invention relates to caps for the radiators of automobiles, and has for its object the provision of a cap having novel 15 means for locking it in position and also equipped with means for admitting air, the air admission means being designed to be closed in cold weather.

Another object is the provision of a cap 20 of this character which is adjustable so that the size of the openings for the air may be regulated at will in a very simple manner.

An additional object is the provision of a cap of this character which will be simple 25 and inexpensive to manufacture, efficient and durable in use, positive in action and a general improvement in the art.

With the above and other objects and advantages in view the invention consists in the details of construction to be hereinafter 30 more fully described and claimed and illustrated in the accompanying drawings, in which:

Figure 1 is a front elevation of a fragment 35 of an automobile radiator showing my cap thereon,

Figure 2 is an elevation at right angles to Figure 1,

Figure 3 is a vertical section through the 40 cap and radiator neck and

Figure 4 is a similar view taken in a plane at right angles to Figure 3.

Referring more particularly to the drawings, the letter A designates a portion of a 45 radiator equipped with a neck B which is externally threaded for engagement thereon of the cap to be described. Near its juncture with the radiator, the neck is formed with a hollow extension 10 within which is 50 slidable a plunger 11 having a head 12 connected with one end of a retractile coil spring 13, and provided exteriorly of the hollow extension with an operating button 14. The other end of the spring is anchored

by being passed through the plunger receiving hole in the neck and subsequently bent or hooked.

Screwed onto the neck is the cap 15 which is formed at its lower edge with a notch 16 normally engaged by the plunger 11 for 60 locking the cap against casual rotation so that it will not jar loose and become lost. The cap is provided in one side with a plurality of air admitting holes 17 which are designed to be closed to a variable extent by 65 means of a disk 18 mounted within the cap and slideable upon rods 19 therein. Secured against the underside of the top of the cap is a plate 20 at the center of which is swiveled a screw 21 which is threaded through 70 the disk 18. By turning the screw in one direction or the other, the disk 18 may be moved to cover the holes 17 partly or entirely as may be desired and as may be found advisable under certain conditions. 75 In actual practice it is intended that the holes be closed in cold weather and opened to a greater or less extent in warm weather. Whenever it is desired to remove the cap it is merely necessary to press the button 14 80 inwardly, so that the head 12 thereof will be disengaged from the notch 16 which will permit the cap to be unscrewed in the usual manner.

While I have shown and described the 85 preferred embodiment of the invention it is of course to be understood that I reserve the right to make such changes in the form, construction and arrangement of parts as will not depart from the spirit of the invention or the scope of the subjoined claims. 90

Having thus described my invention I claim:

1. In a radiator having a filling neck, a hollow projection on the neck, a radially 95 extending spring pressed plunger operating within said hollow projection and extending therebeyond with said extending end carrying a button, and a cap screwed upon the neck and formed with a notch receiving said 100 plunger for preventing casual rotation of the cap.

2. In a radiator having a filling neck, a cap screwed upon the neck and having a notch upon its inner periphery at its open 105 end, a hollow projection on the neck constituting a guide, and an outwardly spring pressed plunger slideable through said hol-

low projection radially of the neck and formed with an upstanding projection engaging within said notch.

3. In a radiator having a filling neck, a cap detachably engaged upon said neck and formed with holes located in its front side, guides arranged longitudinally within the cap, a disk slidable longitudinally within the cap along said guides, and means for moving said disk whereby its periphery will be disposed in or out of obstructing relation to the holes.
- 5 10

4. In a radiator having a filling neck, a cap engaged upon the neck and formed with

holes located at one side, a disk slidably mounted for movement longitudinally within the disk for covering or uncovering said holes and screw means for moving the disk.

5. In a radiator having a filling neck, a cap engaged upon the neck and provided in its side with holes, guides extending longitudinally within the cap, a disk slidable upon said guides and adapted to cover or uncover said holes, and a screw swiveled within the cap and threaded through the disk.
- 20 25

In testimony whereof I affix my signature.

EDWARD RUTT.
